UNITED STATES PATENT OFFICE.

RICHARD SWARTZ, OF PINE BLUFF, ARKANSAS.

DESIGN FOR A WARMING VESSEL.

SPECIFICATION forming part of Design No. 30,091, dated January 31, 1899.

Application filed December 19, 1898. Serial No. 699,777. Term of patent 7 years.

To all whom it may concern:

Be it known that I, RICHARD SWARTZ, a citizen of the United States, residing at Pine Bluff, in the county of Jefferson and State of Arkansas, have invented and produced a new and original Design for Warming Vessels; and I do declare the following to be a full, clear, and exact description of the same, reference being had to the accompanying specification and drawings forming a part thereof.

Figure 1 is a top plan view of my warming vessel, showing my design. Fig. 2 is an edge view. Fig. 3 is a cross-sectional view of Fig. 1 on the line $x x$.

As shown in the drawings, the leading or material feature of my design consists of a corrugated top wall 1, oval-shaped at one end and straight at the other, said wall being provided with an opening 2 and a cap 3 and with a longitudinal concave depression 4, a bottom wall 5, which is parallel with the top wall in all its parts except as to corrugations and the depression 4, and side and end walls 6, which

flare out a little from the bottom wall up to the top wall. 25

Running longitudinally on the inside of the vessel and conforming to the curve thereof are bracing-ribs 7, their upper feet 8 resting against the inner face of the top wall and the lower feet 9 against the inner face of the bottom wall. 30

In face view the vessel is oval at one end and straight at the other. In edge view it is circular, representing the arc of a circle.

The vessel is provided with a handle 10. 35

Having described my invention, what I claim as new, and desire to secure by Letters Patent, is—

The design for a warming vessel as herein shown and described. 40

In testimony whereof I hereunto sign my name in the presence of two witnesses.

RICHARD SWARTZ.

Witnesses:

WILLIAM FRANKLIN COLEMAN,
OLIVER GALBRAITH.
